W. W. GUY

FIREPLACE

Filed Aug. 7, 1925

Patented June 7, 1927.

UNITED STATES PATENT OFFICE.

WALTER W. GUY, OF OAK PARK, ILLINOIS, ASSIGNOR TO COLONIAL FIREPLACE COMPANY, OF CHICAGO, ILLINOIS, A CORPORATION OF ILLINOIS.

FIREPLACE.

Application filed August 7, 1925. Serial No. 48,823.

My present invention relates to fireplaces and more specifically to an improved controlling means for the draft on a fireplace.

Among the objects and advantages of the invention may be enumerated:

First, eliminating the necessity for running rotary shafts or other transmission members through the walls of the fireplace.

Second, maintaining convenience and accuracy of control in spite of such elimination, and

Third, simplifying the mechanical transmission exposed to the heat of the fire.

Further objects and advantages of the invention will become apparent as the description proceeds.

In the accompanying drawings:

Figure 1 is a fore and aft section through a fireplace, indicating the application of a structure according to the invention there-
to.

Figure 2 is a fragmentary similar section showing the parts in a different position.

Figure 3 is a view on line 3-3 of Figure 1 showing the transmission in elevation.

Figure 4 is a sectional view on line 4-4 of Figure 3.

Figure 5 is an elevation of the handle member, and

Figure 6 is a detail section on line 6-6 of Figure 2.

In the embodiment of the invention selected for illustration the fireplace comprises the usual rear wall 10 and front wall 12 between which is formed the throat 14 opening into the flue 16. The damper 18 is in this instance pivoted at 20 on a unitary dome structure including the rear rail 22 and front plate 24. The foregoing structure is old and well known in the art and per se forms no part of the present invention.

A two piece support 26, 28, is suitably fastened in the throat opposite the damper 18, as by fastening it on the plate 24 by machine screws 27. The lifter 28 is in the form of a bell crank lever having one arm pivoted at 30 between lugs 32 on the support, and the other arm connected to the damper by side links 34. The lever is extended back of its angle at 36 and terminates in an arcuate shoe 38 lying in a plane perpendicular to that of the rest of the lever and facing the support 26, 28.

The operating member 40 comprises a cylindrical portion pivotally held between

semi-cylindrical lugs 42 on the support. Above the pivot there is a lateral off-set portion 44 and at the end of the off-set an upright finger 46 terminating in a slight hook at 48. Below the pivot the operating member proper terminates in a flat tang 50 bent outwardly at an angle of approximately 60° to the pivotal axis.

I provide a handle member 52, the main reach of which is a shallow U in cross section adapted to fit over the tang 50. A series of equally spaced holes 54 is formed in the handle member. In assembling the device, registering holes are drilled in the tang 50 and the parts bolted together by bolts 56 as clearly shown in Figure 6. The handle member is preferably of cast iron, and in assembling the unit in any particular fireplace it may be bolted to the tang so as to be of just the right length to project a convenient distance below the lower edge of the front wall 12. If the reach 52 is longer than necessary, the excess at the upper end can be broken off readily by a sharp blow with a hammer.

The lower end of the handle terminates in a target 58 apertured at 60 to receive the end of a poker or the like for swinging the handle from side to side. As the plate 24 is at an angle of substantially 45° to the horizontal, it will be obvious that the 60° bend in the tang 50 will set the handle 52 at an angle inclined about 15° downwardly and rearwardly from the vertical. To operate the device, the handle 52 is swung from side to side, either by inserting a tool in the aperture 60 or merely by pushing against the side of the handle. The movement of the damper 18 in response to the swinging of the handle will depend on the contour of the handle will depend on the contour of the cam face on the shoe 38. The finger 46 of the operating member 40 wipes across this face and pushes the lifter from the position shown in Figure 2 to that of Figure 1. Referring in detail to Figure 4, it will be noted that the ends of the cam face are provided with stop hooks 62 to limit the extreme movement of the parts and that the face of the cam is provided with a plurality of slight irregularities. More specifically, there is a slight pocket 64 at each end, and portions 66 sloping inwardly toward the axis of the operating member, alternating with two slight recessions or portions of lesser inclination at 68. In operating the

device, there will be a material change in the force required to move the handle each time the finger registers with one of the recessions 68. This is of material assistance 5 to the operator in dividing the range of movement of the handle into three substantially equal parts. The inclination of the face of the cam is nowhere sufficiently steep so that the finger will slip back after the operator relieves the handle 52 of the moving force, but he can feel the parts move from closed position into position one-third open, two-thirds open and full open. Thus, after moving the parts one-third open, he can select an intermediate position with considerably greater accuracy than he could if the series of intermediate position were not, in fact, "marked" for him by the variations in resistance to the movement.

Without further elaboration, the foregoing will so fully explain the gist of my invention, that others may, by applying current knowledge, readily adapt the same for use under various conditions of service, 25 without eliminating certain features which may properly be said to constitute the essential items of novelty involved, which items are intended to be defined and secured to me by the following claims.

30 I claim:

1. A fireplace having a damper pivoted on a horizontal axis, a lifter pivoted on a parallel axis, a link connecting said lifter and damper, an operating member pivoted on an axis in a vertical plane perpendicular to the damper axis, an offset finger on said operating member, and a generally arcuate cam carried by said lifter in operative contact with said finger, the axis of said operating member being inclined downwardly and forwardly, said operating member having a handle portion extending from its front and lower end, said handle portion when in the vertical plane of the axis of the operating member extending downwardly and rearwardly and being accessible from in front of the fireplace, said cam having a plurality of portions of greater slope alternating with portions of less slope to guide the operator in setting the damper, all said portions having slopes providing a friction lock against movement of the handle by the damper.

2. A fireplace having a pivoted damper, a pivoted lifter, a link connecting said lifter and damper, a pivoted operating member, a finger on said operating member, and a cam carried by said lifter in operative contact with said finger, said operating member having a handle portion extending downwardly and rearwardly and being accessible from in front of the fireplace.

3. A fireplace having a pivoted damper, a pivoted lifter, a link connecting said lifter and damper, a pivoted operating member,

a finger on said operating member, and a cam carried by said lifter in operative contact with said finger, said cam having a plurality of portions of greater slope alternating with portions of less slope to guide the operator in setting the damper, all said portions having slopes providing a friction lock against movement of the handle by the damper.

4. A fireplace having a pivoted damper, a 75 lifter, a link connecting said lifter and damper, an operating member, and a cam carried by said lifter in operative contact with said operating member.

5. A fireplace having a pivoted damper, 80 a lifter, a link connecting said lifter and damper, an operating member, and a cam carried by said lifter in operative contact with said operating member, said cam having a plurality of portions of greater slope alternating with portions of less slope to guide the operator in setting the damper.

6. A fireplace having a pivoted damper, 85 a lifter, a link connecting said lifter and damper, an operating member, and a cam carried by said lifter in operative contact with said operating member, said cam having a plurality of portions of greater slope alternating with portions of less slope to guide the operator in setting the damper, 90 all said portions having slopes providing a friction lock against movement of the handle by the damper.

7. A fireplace having a pivoted damper, 95 a lifter, a link connecting said lifter and damper, an operating member, and a cam carried by said lifter in operative contact with said finger, said operating member having a handle portion extending downwardly and being accessible from in front of the fireplace.

8. A fireplace dome comprising a frame, 100 a damper, a pivoted element having one end projecting down and accessible from in front of the fireplace, said end being apertured to receive the end of a poker for swinging it from side to side, and a linkage between said pivoted element and said damper for moving said damper from closed to open position upon movement of said element from one extreme position to the other and vice versa, said linkage permitting said damper to fall by gravity and being friction locked in any position, said linkage offering variable resistance to the opening movement with two minima at intermediate positions.

9. A fireplace dome comprising a frame, 105 a damper, a pivoted element having one end projecting down and accessible from in front of the fireplace, said end being apertured to receive the end of a poker for swinging it from side to side, and a linkage between said pivoted element and said damper for moving said damper from closed 110 to open position upon movement of said element from one extreme position to the other and vice versa, said linkage permitting said damper to fall by gravity and being friction locked in any position, said linkage offering variable resistance to the opening movement with two minima at intermediate positions.

to open position upon movement of said element from one extreme position to the other and vice versa, said linkage permitting said damper to fall by gravity and being friction locked in any position, said linkage offering variable resistance to the opening movement.

10. A fireplace dome comprising a frame, a damper, a pivoted element having one end projecting down and accessible from in front of the fireplace, said end being apertured to receive the end of a poker for swinging it from side to side, and a linkage

between said pivoted element and said damper for moving said damper from closed to open position upon movement of said element from one extreme position to the other and vice versa, said linkage permitting said damper to fall by gravity and being friction locked in any position, said linkage offering variable resistance to the opening movement with a minimum at an intermediate position.

In witness whereof, I hereunto subscribe my name this 3rd day of August, 1925.

WALTER W. GUY.
